UNITED STATES PATENT OFFICE.

JEAN F. WEBB, OF DENVER, COLORADO.

SEMAPHORE.

No. 825,991.

Specification of Letters Patent.

Patented July 17, 1906.

Application filed July 21, 1905. Serial No. 270,665.

To all whom it may concern:

Be it known that I, JEAN F. WEBB, residing at Denver, in the county of Denver and State of Colorado, have invented certain new and useful Improvements in Semaphores, of which the following is a specification.

My invention relates to certain new and useful improvements in semaphores, and it primarily seeks to provide an electrically-operated semaphore in which means are provided for presenting a "blade-signal" as well as a "light-signal;" and in its generic nature my invention comprises a supporting-frame, a signaling-shaft, carried by the supporting-frame, which controls the signals, both blade and light, means for preventing the shaft from turning except in a single direction, means for locking the shaft from turning in such single direction, electrically-controlled means for first releasing said locking means and then turning the shaft in one direction to change the signals, and a casing for the operative parts of the apparatus.

The present invention primarily has for its object to provide a semaphore apparatus of this character of a very simple construction which can be easily and cheaply manufactured and which will readily and effectively serve its intended purposes.

With other objects in view than have heretofore been enumerated the invention also comprehends certain novel construction, combination, and arrangement of parts, all of which will be first described in detail and then be specifically pointed out in the appended claims, reference being had to the accompanying drawings, in which—

Figure 1 is a perspective view of my invention complete. Fig. 2 is a similar view, the housing being removed. Fig. 3 is a face view of my invention, the housing-cover being shown open. Fig. 4 is an end elevation of my invention, the housing being shown in section. Fig. 5 is a cross-section taken on the line 5 5 of Fig. 3 looking in the direction of the arrow. Fig. 6 is a detail perspective view of the signaling-shaft and its carried parts. Fig. 7 is a vertical longitudinal section of a slightly-modified form of my invention.

Referring now to the accompanying drawings, in which like numerals and letters of reference indicate like parts in all of the figures, 1 designates the signal-shaft, which is mount-

ed in bearings 2^a 2^a in the standards 2 2, 55 which are secured to a post 2^b by lag-screws 2^c 2^c and which are connected together at the top by a cross spacing-bar 18, as shown.

Mounted on the shaft 1 between the supports or standards 2 2 is a ratchet-wheel 3, 60 having four notch-faces or teeth 3^a arranged peripherally and ninety degrees apart, and the notches or teeth 3^a are arranged in a direction opposite to that in which the shaft is designed to normally turn, and the shaft 1 is 65 prevented from turning backward by a pawl 8, which is fulcrumed on a stud-bolt 9, secured to the support 2, and which engages the ratchet-wheel 3. The pawl 8 is held on the bolt 9 by a pin 9^a, as shown. The pawl 8 and 70 the ratchet 3 serve as a means for preventing rotation of the shaft in a direction reversely to that of its normal movement.

Secured by a set-screw 4^a to the shaft 1, adjacent the ratchet 3, is a collar 4 to which a 75 second ratchet-wheel 5 on the shaft 1 is secured by a screw or rivet 4^b. The ratchet 5 has four teeth 5^a peripherally arranged and spaced ninety degrees apart, but facing in a direction opposite to those 3^a on the ratchet 80 3 and facing in the same direction as the direction of normal rotation of the shaft 1. A pawl 10, fulcrumed on a second stud-bolt 11, secured to the standard 2, engages with the ratchet 5 to prevent rotation of the shaft 1 in 85 its normal direction, thus normally locking the shaft from rotation. The pawl 10 has a trip-arm 10^a, having a bevel-edge 10^b for a purpose presently understood.

Mounted on the shaft 1, adjacent the 90 ratchet 5, and secured to turn therewith by the screw 4^b, is a pair of disks 6 6, spaced a suitable distance apart and joined by four cross-pins 6^a 6^a, as shown. The pins 6^a 6^a are set ninety degrees apart, as shown, and some 95 distance in from the periphery of the disks 6 6 to permit passage of the operating-bar 13 between the disks 6 6. The bar 13 is secured to the plunger or piston 17^a of the electromotor 17, hereinafter again referred to, and the 100 said bar 13 is preferably constructed of brass or other non-magnetic material and is provided near its lowermost end with a hook 13^a for engaging and operating the pins 6^a 6^a to turn the shaft 1 in the direction of the arrow. 105

The bar 13 carries a pin or stud 14 for engaging the arm 10^a of the pawl 10 to release the ratchet 5 just prior to the time the hook

13^a engages the pin 6^a to turn the shaft 1 through one-fourth revolution, the stud or pin 14 leaving the arm 10^a of the pawl 10 just after the shaft commences to turn, thus allowing the pawl 10 to drop into contact with the periphery of the ratchet 5 to engage the next ratchet-tooth 5^a and prevent the shaft turning through more than one-fourth revolution at each operation. As the bar 13 again drops to its initial position, as will be more fully understood presently, by reason of the pivotal connection of the motor 17 with the bar 13 the pin 14 passes over the beveled portion 10^b of the arm 10^a of the pawl and drops to its initial position. The bar 13 has a second hook 13^b near its upper end, which when the bar is in its lowermost position engages the stud-bolt 12 on the support 2, thus holding the bar from dropping downwardly too far and maintaining it in proper position to engage the pins 6^a 6^a of the disks 6 6.. The bar 13 is connected at 16 to the piston or plunger 17^a of the motor 17.

The motor 17, which may be of any appropriate type of electric motor, is shown in the drawings as a solenoid magnetic reciprocating motor comprising a movable core or plunger 17^a and the fixed core 17^c, the whole being surrounded by a casing 17^b, of magnetic material, to form an "iron-clad" housing for the motor. The casing 17^b has extensions provided with apertures 17^d 17^d to permit it being mounted upon the cross-brace 18, where it is held in proper position by the pins or keys 19^a 19^a, as shown, to allow the motor to have a free pivotal movement and permit proper action of the bar 13.

Mounted on the support 2, but insulated therefrom, and arranged adjacent one another and normally out of contact with one another is a pair of contact-plates 20^a 20^a, held in position by the bolts 20^b 20^b, to which the wires 21 22 of the return signal-circuit 23 connect. The return signal-circuit 23 is operated whenever the plates 20^a 20^a are brought into contact with one another by the pin 15 on the bar 13, which operation occurs whenever the bar 13 is raised to the limit of its movement.

50 The operating-circuit 45 has its terminals 45^a 45^a connected to the winding of the motor 17, so that when the switch S is closed the motor 17 will operate to turn the shaft 1 through one-fourth of a revolution.

55 Secured to the standard 2 by bolts 34^a 34^a is a bracket 34, to which a lamp-holder or ring 33 is secured. A lamp 29, of the usual long-burning railway-switch type, is held in the holder 33, as shown, a smoke-bell 32 being supported over the chimney 30 of the lamp 29 by a rod 31, secured to the holder 33.

24 designates a collar secured to the shaft 1 by a set-screw 41, and the collar 24 carries a plurality of radial arms 24^a equal in number to the teeth on the ratchet 5 and arranged

ninety degrees apart, as shown. To the upper end of each arm 24^a is a lens-holding rim 26, which is secured thereto by bolts 26^a and pins 26^b, and to hold the lens 28^a 28^b in place on the rims 26 I provide clamps 27 27, as shown. The lenses 28^a 28^a are red to indicate "danger," while the lenses 28^b are colorless to indicate "safety."

The shaft 1, which may be either tubular or solid, preferably has its ends split to receive the signal-plates 43^a 43^b, which are secured thereto by bolts 44^a 44^a, as shown. The blade 43^a is arranged at right angles to the blade 43^b, so that only one blade will be visible to the engineer at a time, the blade 43^a being white to indicate "safety," while the blade 43^b is red to indicate "danger."

Secured to the post 2^b over the standards 22 and the operative mechanism of my semaphore is a casing or housing 46, which has a door 46^a in its front, which door 46^a is hinged at its upper end at 49 to the casing and is slotted, as at 46^b, at its lower end to coöperate with the staple 50 on the post 2^b and is secured by a lock 51, as shown.

47 designates a window in the door 46^a, which is in horizontal alinement with the lamp 29, and a second window 47 in the back wall of the housing 46 to permit the lamp-signal being seen by the engineer of an approaching train. Suitable apertures 43^a 48^a are provided in the housing sides to permit passage of the shaft 1, as shown.

So far as described the manner in which my invention operates will be best explained as follows: Assume the signal to be set at "safety" with the blade 43^a visible and the transparent colorless lenses 28^b in alinement with the lantern 29 and the apertures 47 47 in the casing 46 to indicate a safety-signal. Now assume that it is desired to set the semaphore to its danger-indicating position. The operator at the signal-tower closes the switch S in the operating-circuit, thus energizing the motor 17, causing its plunger 17^a to be drawn up and carry with it the bar 13. As the bar 13 starts on its upward movement the pin 14 will engage the arm 10^a of the pawl 10 and release it from engagement with the ratchet 5. As soon as the pawl 10 is released from engagement with the ratchet 5 the bar 13 continuing its upward movement has its hook portion 13^a brought into engagement with the pin 6^a of the disks 6 6 and turns the shaft 1 in the direction of the arrow. Just after the pin 14 has released the pawl 10 it passes out of engagement with the arm 10^a of the pawl 10 and allows the pawl 10 to again drop into engagement with the periphery of the ratchet 5, so as to stop the rotation of the shaft in the direction of the arrow when it is moved through one-fourth revolution. When this position is reached, the blade 43^a is horizontal, while the blade 43^b is vertical, thus showing the red blade or danger-signal. At 130

the same time the arms 24^a are moved through one-fourth revolution to bring the lenses 28^a in alinement with the apertures 47 47 and the lamp 29 to show a red light and 5 indicate a danger-signal. As the bar 13 reaches the limit of its upward stroke the pin 15 will engage the contacts 20^a 20^a and close the return signal-circuit, thus indicating to the tower operator that the semaphore has 10 been moved to its proper position. The operator then opens the switch S to deenergize the motor 17, thus allowing the plunger 17^a and the bar 13 to drop by gravity to its initial 15 position, the pin 14 passing over the beveled portion of the arm 10^a of the pawl 10 and dropping into position, while the hook 13^a likewise passes over the next pin 6^a and drops into position. At the same time the hook 13^b of the bar 13 drops over the stud 12, 20 which holds the bar 13 in proper position to engage the pin 6^a for performing the next movement. When it is again desired to set the signal to its safety position, the operator merely closes the switch S, as before, when the 25 foregoing operation will again take place, with the exception that the next signal set will be "safety" instead of "danger," the preceding signal. Thus it will be seen that the shaft 1 rotates in one direction to alternately expose danger and safety signals and also operates an indicating-signal at the tower operator's office whenever the semaphore has 30 been operated.

In Fig. 7 I have shown a slightly-modified form of my invention in which the signal-shaft 100 is arranged vertically and passes through bearing-apertures 65^x in a cross-bar 65, secured to the standards 2 2 in lieu of the rod 18. The motor 17 is preferably fulcrumed 35 on a rod 118, mounted in a bearing 2^x in the standard 2 and a bearing 63^x in the bracket 33, which is bolted at 64^a to the cross-bar 65. The shaft 100 has its lower end provided 40 with a cone-bearing 54, which co-operates with the ball-bearing 55 in the lower cross-bar 52, which is secured to the standards 2 2 by bolts 61, as shown. The disks 3, 5, and 6 6; together with the collar 4 in this form of my invention, are mounted on a shaft 105, which is 45 journaled in a bearing in the standard 2 and in a second bearing 43 in the supplemental bracket-standard 53, which is secured to the cross-bar 52 and the standard 2 by the bolts 61 and the screw 62, as shown. The 50 shaft 105 carries a bevel-pinion 58 of forty-five degrees pitch, which meshes with a second bevel-pinion 57 on the shaft 100, so that the rotary motion of the shaft 105 is imparted to the shaft 100, as will be clearly understood 55 by reference to the drawings.

In the form of my invention shown in Fig. 7 the semaphore-signals are in the nature of disk signals, which are secured to the shaft 100 above the housing 46 and which comprise 60 the disks 43^a and 43^b, which are white and

red, respectively. Above the signal-disks 43^a 43^b the signal-lantern 129 is secured to the bracket 69^a, which bracket is secured to the shaft 100 by a collar 69, as shown, and the lamp in this case is inclosed within the 70 usual lamp-casing 29^x and is provided with four lensed apertures 128^a 128^a and 128^b 128^b, alternate ones of which are red, while the others are white to correspond with the disk signals 43^a 43^b to show safety or danger 75 signals, as the case may be. In this form of my invention also the housing 46 is made with a conical top to form a watershed and a washer 68 is carried by the shaft 100 to prevent ingress of water into the casing 46 80 through the top thereof. In other respects this form of my invention is constructed along the same lines as that shown in Figs. 1 to 8, inclusive, of the drawings. The operation of the form of my invention shown in 85 Fig. 7 is as follows: The operator closes the switch S to energize the motor 17, thus drawing up the plunger 17^a and rotating the shaft 105 in the same manner as the shaft 1 in Figs. 1 to 8, inclusive, is rotated. The motion of 90 the shaft 105 is imparted to the shaft 100, which is turned through one-fourth revolution at each operation of the motor 17. The signal-circuit is operated in the same manner as before explained for the invention shown 95 in Figs. 1 to 8, and as soon as the signal has been moved the switch S is again opened.

From the foregoing it will be seen that I have provided a very simple and effectively-operating semaphore-signal capable of use 100 either as a track-signal or as a pole-signal, as the case may be. Furthermore, I have provided a semaphore in which the signal-shaft is rotated intermittently in one direction only, thus insuring a more perfect operation 105 of the apparatus than is possible where the shafts are turned in one direction and then turned back again.

Attention is particularly called to the pawls 8 and 10, which automatically lock the 110 semaphore, so that it cannot be turned in either direction by the wind or moved by any one tampering with the signal alone, but can be only moved by the operation of the motor 17 when the pawl 10 is released, and 115 then only in a direction in which the shafts 1 or 100 are designed to move.

From the foregoing description, taken in connection with the accompanying drawings, it is thought that the complete construction, 120 operation, and many advantages of my invention will be readily understood by those skilled in the art to which it appertains.

Having thus described my invention, what I claim, and desire to secure by Letters Patent, is—

1. In a semaphore of the class described, a rotatably-mounted signaling-shaft, means for preventing said shaft from rotating in one direction, means for locking said shaft from 130

rotating in the other direction, and electrically-operating means for first releasing said locking means and then rotating said shaft in said second direction, substantially as shown and described.

2. A semaphore of the class described, comprising a rotatable signal-carrying shaft, means for locking said shaft from rotation, electrically-operated means for releasing said locking means during the initial position of its movement and rotating said semaphore-shaft during the remaining portion of its movement, substantially as shown and described.

15 3. A semaphore comprising supporting-standards, a rotatably-mounted signaling-shaft mounted in said standards, means for preventing rotation of said shaft in one direction, means for locking said shaft from rotation in the other direction, electrically-controlled devices for first tripping said locking means and then rotating said shaft substantially as shown and described.

4. A semaphore comprising supporting-standards, a rotatably-mounted signaling-shaft mounted in said standards, means for preventing rotation of said shaft in one direction, means for locking said shaft from rotation in the other direction, electrically-controlled devices for first tripping said locking means and then rotating said shaft and a return signal-circuit closable by said shaft-turning devices as they reach the limit of their operative movement, substantially as shown and described.

35 5. In an apparatus of the class described, a rotatably-mounted signaling-shaft, means for preventing said shaft from rotating in one direction, means for locking said shaft from rotating in the other direction, and means for first releasing said locking means and then rotating said shaft in said second direction, and a return signaling-circuit including a circuit-closer co-operatively connected with the 45 semaphore-operating mechanism for operating a return-signal at each movement of the semaphore-signals, substantially as shown and described.

6. In a signaling apparatus, a revolving 50 semaphore, means for rotating the semaphore always in the same direction and displaying alternately safety and danger signals, and a return signaling-circuit including a circuit-closer co-operatively connected with the 55 semaphore-operating mechanism for operating a return-signal at each movement of the semaphore-signals, substantially as shown and described.

7. A revolving semaphore, electrically-controlled devices for revolving said semaphore always in the same direction to alternately display safety and danger signals, and a return signaling-circuit including a circuit-closer co-operatively connected with the 65 semaphore-operating mechanism for operat-

ing a return-signal at each movement of the semaphore-signals substantially as shown and described.

8. A revolving semaphore, electrically-controlled mechanism for intermittently rotating said semaphore always in the same direction to alternately display safety and danger signals, and a return signaling-circuit including a circuit-closer co-operatively connected with the semaphore-operating mechanism 75 for operating a return-signal at each movement of the semaphore, substantially as shown and described.

9. A semaphore of the class described, comprising standards, a rotatably-mounted 80 signaling-shaft mounted in said standards, means for preventing rotation of said shaft in one direction, means for locking said shaft from rotation in the other direction, electrically-controlled devices for first tripping said 85 locking means and then rotating said shaft, and a return signaling-circuit including a circuit-closer co-operatively connected with the semaphore-operating mechanism for operating a return-signal at each movement of the 90 semaphore-signals substantially as shown and described.

10. An apparatus of the class described, comprising a support, a rotatable signal-shaft mounted therein, means for preventing said 95 shaft from rotating backward, means for locking said shaft from rotating forward, means for first releasing said locking means and then rotating the shaft forwardly, all being arranged substantially as shown and described.

11. An apparatus of the class described, comprising a support, a rotatable signal-shaft mounted therein, means for preventing said shaft from rotating backward, means for locking said shaft from rotating forward, means for first releasing said locking means and then rotating the shaft forwardly, signal-lenses carried by said shaft and rotatable therewith, and a signal-lamp co-operating 110 with said lenses to have its light-rays intercepted thereby substantially as shown and described.

12. An apparatus of the class described, comprising a support, a rotatable signal-shaft 115 mounted therein, means for preventing said shaft from rotating backward, means for locking said shaft from rotating forward, means for first releasing said locking means and then rotating the shaft forwardly, signal-lenses carried by said shaft and rotatable therewith, a signal-lamp co-operating with said lenses to have its light-rays intercepted thereby, and a casing for the whole having windows for registering with said signal-lamp, substantially as shown and described.

13. An apparatus of the class described, comprising a support, a rotatable signal-shaft mounted therein, means for preventing said shaft from rotating backward, means for

- locking said shaft from rotating forward, means for first releasing said locking means and then rotating the shaft forwardly, signal-lenses carried by said shaft and rotatable therewith, a signal-lamp coöperating with said lenses to have its light-rays intercepted, and a casing for the whole having windows for registering with said signal-lamp, said signal-shaft projecting through said casing, and carrying signal-blades at each end, substantially as shown and described.
14. An apparatus of the class described, comprising a support, a rotatable signal-shaft mounted therein, means for preventing said shaft from rotating backward, means for locking said shaft from rotating forward, means for releasing said locking means and then rotating the shaft forwardly, signal-lenses carried by said shaft and rotatable therewith, a signal-lamp coöperating with said lenses to have its light-rays intercepted thereby, a casing for the whole having windows for registering with said lamp-signal, contact devices mounted on said support, and means coöperatively connected with said releasing and rotating means for closing said contacts to close an electric circuit, substantially as shown and described.
15. An apparatus of the class described, comprising a support, a rotatable signal-shaft mounted therein, means for preventing said shaft from rotating backward, means for locking said shaft from rotating forward, means for first releasing said locking means and then rotating the shaft forwardly, signal-lenses carried by said shaft and rotatable therewith, a signal-lamp coöperating with said lenses to have its light-rays intercepted, a casing for the whole having windows for registering with said signal-lamp, said signal-shaft projecting through said casing, and carrying signal-blades at each end, contact devices mounted on said support and means coöperatively connected with said releasing and rotating means for closing said contacts to close an electric circuit, substantially as shown and described.
16. An apparatus of the class described, comprising a pair of supporting-standards, a supporting-post to which said standards are secured, a signal-shaft mounted in bearings in said standards, with its ends projecting beyond the same, signal-blades secured one at each end of said signal-shaft and at right angles to each other, a plurality of radial arms secured to said signaling-shaft and arranged in diametrically opposite pairs, one pair being spaced ninety degrees from the other, an electromechanically-controlled means for turning said shaft in one direction one-fourth revolution at a time, a signal-lamp held adjacent said shaft, and lenses carried by said radial arms for coöperating with said signaling-lamp, all being arranged substantially as shown and described.
17. An apparatus of the class described, comprising a pair of supporting-standards, a supporting-post to which said standards are secured, a signal-shaft mounted in bearings in said standards with its ends projecting beyond the same, signal-blades secured one at each end of said signal-shaft and at right angles to each other, a plurality of radial arms secured to said signaling-shaft, and arranged in diametrically opposite pairs, one pair being spaced ninety degrees from the other, electromechanically - controlled means for turning said shaft in one direction one-fourth revolution at a time, a signal-lamp held adjacent said shaft, lenses carried by said radial arms for coöperating with said signaling-lamp, and a casing for the whole having windows for registering with said signal-lamp, said signal-shaft projecting through said casing with its blades on the outside thereof, substantially as shown and described.
18. An apparatus of the class described, comprising a pair of supporting-standards, a spacing-bar secured between said standards at the top, an electric motor secured to said spacing-bar, a signal-shaft, signaling-blades secured to said signal-shaft, a ratchet secured to said signal-shaft and a pawl mounted on said support for coöperating with said ratchet to prevent the shaft rotating backward, a second ratchet on said signal-shaft and a second pawl on said support for locking said shaft from rotating forward, means connected with said motor for first releasing said locking-pawl and then rotating the shaft in its forward direction, all being arranged substantially as shown and described.
19. An apparatus of the class described, comprising a pair of supporting-standards, a spacing-bar secured between said standards at the top, an electric motor secured to said cross-bar, a signal-shaft, signaling-blades secured to said signal-shaft, a ratchet secured to said signal-shaft and a pawl mounted on said support for coöperating with said ratchet to prevent the shaft rotating backward, a second ratchet on said signal-shaft and a second pawl on said support for locking said shaft from rotating forward, means connected with said motor for first releasing said locking-pawl and then rotating the shaft in its forward direction, and a casing for the whole, said signaling-shaft projecting through said casing with its blades on the outside thereof.
20. An apparatus of the class described, comprising a pair of supporting-standards, a spacing-bar secured between said standards at the top, an electric motor secured to said cross-bar, a signal-shaft, signaling-blades secured to said signal-shaft, a ratchet secured to said signal-shaft and a pawl mounted on said support for coöperating with said ratchet, to prevent the shaft rotating backward, a second ratchet on said signal-shaft, and a sec-

ond pawl mounted on said support for locking said shaft from rotating forward, means connected with said motor for first releasing said locking-pawl and then rotating the shaft

5 in its forward direction, a bracket secured to said support, a signal-lamp carried by said bracket, a plurality of radial arms arranged ninety degrees apart and secured to said shaft, lenses secured to said radial arms for coöperating with said signal-lamp, all being arranged substantially as shown and described.

21. An apparatus of the class described, comprising a pair of supporting-standards, a spacing-bar secured between said standards at the top, an electric motor secured to said cross-bar, a signal-shaft, signaling-blades secured to said signal-shaft, a ratchet secured to said signal-shaft and a pawl mounted on said support for coöperating with said ratchet, to prevent the shaft rotating backward, a second ratchet on said signal-shaft, and a second pawl mounted on said support for locking said shaft from rotating forward, means connected with said motor for first releasing said locking-pawl and then rotating the shaft in its forward direction, a bracket secured to said support, a signal-lamp carried by said bracket, a plurality of radial arms arranged ninety degrees apart and secured to said shaft, lenses secured to said radial arms for coöperating with said signal-lamp, and a casing for the whole having windows for registering with said signal-lamp, said signaling-shaft having its ends projected through the casing with its signaling-blades secured to said projecting ends, substantially as shown and described.

22. An apparatus of the class described, comprising a pair of standards, a signaling-shaft transversely mounted in bearings in said standards, a ratchet secured to said signaling-shaft, a pawl coöperating with said ratchet for preventing the shaft from rotating backward, a second ratchet secured to 40 said shaft, a pawl coöperating with said second ratchet for locking the shaft from rotating forward, said locking-pawl having a finger, a pair of disks mounted on said shaft and spaced-apart, cross-pins securing said disks 45 together, a bar reciprocally mounted between said disks, said bar having a hook for coöperating with said disk-pins, said bar having a pin for engaging the finger of said locking-pawl to release the same, an electromagnet 50 for reciprocating said bar, said bar being arranged to first release the locking-pawl, and on further movement to rotate the shaft in a forward direction, all being arranged substantially as shown and described.

6, 23. In an apparatus of the class described, comprising a pair of supporting standards, a signaling-shaft transversely mounted in bearings in said standards, a ratchet secured to said signaling-shaft, a pawl co-operating

with said ratchet for preventing the shaft 65 from rotating backward, a second ratchet secured to said shaft, a pawl coöperating with said second ratchet for locking the shaft from rotating forward, said locking-pawl having a finger, a pair of disks mounted on said shaft, 70 and spaced - apart, cross - pins securing said disks together, a bar reciprocally mounted between said disks, said bar having a hook for coöperating with said disk-pins, said bar having a pin for engaging the finger of said locking-pawl to release the same, an electromagnet for reciprocating said bar, said bar being arranged to first release the locking-pawl, and on further movement to rotate the shaft in a forward direction, and means 75 mounted on the supporting-standards and coöperating with said bar for holding the bar in operative engagement with the disks, substantially as shown and described.

24. An apparatus of the class described, comprising a pair of supporting-standards, a signaling-shaft transversely mounted in bearings in said standards, a ratchet secured to said signaling-shaft, a pawl coöperating with said ratchet for preventing the shaft from rotating backward, a second ratchet secured to said shaft, a pawl coöperating with said second ratchet for locking the shaft from rotating forward, said locking-pawl having a finger, a pair of disks mounted on said shaft, and spaced-apart, cross-pins securing said disks together, a bar reciprocally mounted between said disks, said bar having a hook for coöperating with said disk-pins, said bar having a pin for engaging the finger of said locking-pawl to release the same, an electromagnet for reciprocating said bar, said bar being arranged to first release the locking-pawl, and on further movement to rotate the shaft in a forward direction, and means mounted on the supporting-standards and coöperating with said bar for holding the bar in operative engagement with the disks, a bracket secured to said supporting-standards, a signal-lamp carried by said bracket, a plurality of lenses carried by said signaling-shaft and rotatable therewith, for coöperating with said signal-lamp substantially as shown and described. 105 110 115

25. In an apparatus of the class described, comprising a pair of supporting-standards, a signaling-shaft transversely mounted in bearings in said standards, a ratchet secured to said signaling-shaft, a pawl coöperating with said ratchet for preventing the shaft from rotating backward, a second ratchet secured to said shaft, a pawl coöperating with said second ratchet for locking the shaft from rotating forward, said locking-pawl having a finger, a pair of disks mounted on said shaft, and spaced apart, cross-pins securing said disks together, a bar reciprocally mounted between said disks, said bar having a hook for coöperating with said disk-pins, said bar

having a pin for engaging the finger of said locking-pawl to release the same, an electromagnet for reciprocating said bar, said bar being arranged to first release the locking-pawl, and on further movement to rotate the shaft in a forward direction, and means mounted on the supporting-standards and coöperating with said bar for holding the bar in operative engagement with the disks, a bracket secured to said supporting-standards, a signal-lamp carried by said bracket, a plurality of lenses carried by said signaling-shaft and rotatable therewith, for coöperating with said signal-lamp, a casing for the whole having windows for registering with said signal-lamp substantially as shown and described.

26. An apparatus of the class described, comprising a pair of supporting-standards, a signaling-shaft transversely mounted in bearings in said standards, a ratchet secured to said signaling-shaft, a pawl coöperating with said ratchet for preventing the shaft from rotating backward, a second ratchet secured to said shaft, a pawl coöperating with said second ratchet for locking the shaft from rotating forward, said locking-pawl having a finger, a pair of disks mounted on said shaft, and spaced-apart, cross-pins securing said disks together, a bar reciprocally mounted between said disks, said bar having a pin for engaging the finger of said locking-pawl to release the same, an electromagnet for reciprocating said bar, said bar being arranged to first release the locking-pawl, and on further movement to rotate the shaft in a forward direction, and means mounted on the supporting-standards and coöperating with said bar for holding the bar in operative engagement with the disks, a bracket secured to said supporting-standards, a signal-lamp carried by said bracket, a plurality of lenses carried by said signaling-shaft and rotatable therewith, for coöperating with said signal-lamp, a casing for the whole having windows for registering with said signal-lamp, said signaling-shaft projecting through said casing, signaling-blades carried by the ends of said signaling-shaft, and a smoke-bell supported over the chimney of said signal-lamp, substantially as shown and described.

27. An apparatus of the class described, comprising a pair of supporting-standards, a signaling-shaft transversely mounted in bearings in said standards, a ratchet secured to said signaling-shaft, a pawl coöperating with said ratchet for preventing the shaft from rotating backward, a second ratchet secured to said shaft, a pawl coöperating with said second ratchet for locking the shaft from rotating forward, said locking-pawl having a finger, a pair of disks mounted on said shaft, and spaced-apart, cross-pins securing said disks together, a bar reciprocally mounted between said disks, said bar having a pin for engaging the finger of said locking-pawl to release the same, an electromagnet for reciprocating said bar, said bar being arranged to first release the locking-pawl, and on further movement to rotate the shaft in a forward direction, means mounted on the supporting-standards and coöperating with said bar for holding the bar in operative engagement with the disks, a bracket secured to said supporting-standards, a signal-lamp carried by said bracket, a plurality of lenses carried by said signaling-shaft and rotatable therewith, for coöperating with said signal-lamp, a casing for the whole having windows for registering with said signal-lamp, said signaling-shaft projecting through said casing, signaling-blades carried by the ends of said signaling-shaft, and a smoke-bell supported over the chimney of said signal-lamp, substantially as shown and described.

28. A revolving semaphore, a mechanism for revolving said semaphore always in the same direction to display alternately safety and danger signals, means for locking said semaphore from rotation and an electric motor for first releasing said locking means and then operating said revolving mechanism.
